(57) CLAIM

The ornamental design for a complex image player, as shown and described.

DESCRIPTION

FIG. 1 is a top front perspective view of a complex image player showing our new design.

FIG. 2 is a front elevational view thereof.

FIG. 3 is a rear elevational view thereof.

FIG. 4 is a left side elevational view thereof, the right side being a mirror image;

FIG. 5 is a top plan view thereof; and,

FIG. 6 is a bottom plan view thereof.
